ATTORNEY.

UNITED STATES PATENT OFFICE.

SAGHATIEL G. MANDALIAN, OF NORTH ATTLEBORO, MASSACHUSETTS, AS-SIGNOR TO FIRM, CASPER AND MANDALIAN, OF MASSACHUSETTS.

DESIGN FOR A HAT-PIN.

No. 37,550.

Specification for Design.

Patented Sept. 12, 1905.

Application filed June 12, 1905. Serial No. 264,960. Term of patent 7 years.

To all whom it may concern:

Be it known that I, SAGHATIEL G. MANDALIAN, a citizen of the United States, residing at North Attleboro, in the county of Bristol and State of Massachusetts, have invented a new, original, and ornamental Design for a Hat-Pin, of which the following is a specification, reference being had therein to the accompanying drawing.

The figure is a side elevation of a hat-pin, showing my new design.

I claim—

The ornamental design for a hat-pin as shown.

SAGHATIEL G. MANDALIAN.
